INSPECTION LIGHT

William K. Becker, Cooper Township, Kalamazoo County, Mich., assignor to Aero-Motive Manufacturing Company, Kalamazoo, Mich.

Filed Aug. 22, 1960, Ser. No. 61,835

Term of patent 14 years

(Cl. D48—20)

I claim:

The ornamental design for an inspection light, as shown.
